UNITED STATES PATENT OFFICE.

HARRIET M. ROBINSON, OF SEATTLE, WASHINGTON.

DESIGN FOR A DOLL.

Application filed May 13, 1922. Serial No. 2,218. Term of patent 14 years.

To all whom it may concern:

Be it known that I, HARRIET M. ROBINSON, a citizen of the United States, residing at Seattle, in the county of King and State of Washington, have invented a new, original, and ornamental Design for a Doll, of which the following is a specification, reference being had to the accompanying drawing, forming part hereof, wherein—

Fig. 2 is a view in rear elevation thereof.
Fig. 3 is a view in side elevation thereof, and

Fig. 4 is a top plan view of the same.

I claim:

The ornamental design for a doll, as shown.

HARRIET M. ROBINSON.
